UNITED STATES PATENT OFFICE

158,542

ROADSIDE SERVICE STATION

P. Bob Attwell, Seattle, Wash.

Application April 6, 1948, Serial No. 145,559

Term of patent 7 years

(CL. D13—1)

To all whom it may concern:

Be it known that I, P. Bob Attwell, a citizen of the United States of America, residing at Seattle, in the county of King, and State of Washington, have invented a new, original, and ornamental Design for a Roadside Service Station, of which the following is a specification, reference being had to the accompanying drawings, forming part thereof.

In the drawings:

Figure 1 is a perspective view of a roadside service station, showing my new design.

Figure 2 is a front elevation of the same.

Fig. 3 is a side elevation of one side of the same.

Fig. 4 is a side elevation of the other side of the same.

I claim:

The ornamental design for a roadside service station, as shown.

P. BOB ATTWELL.
